(57) **CLAIM**

The ornamental design for a gaming machine button panel, as shown and described herein.

DESCRIPTION

FIG. 1 is a front perspective view of a gaming machine button panel of one embodiment of our new design.

FIG. 2 is a front view of the gaming machine button panel of FIG. 1.

FIG. 3 is a top view of the gaming machine button panel of FIG. 1.

FIG. 4 is a bottom view of the gaming machine button panel of FIG. 1.

FIG. 5 is a left side view of the gaming machine button panel of FIG. 1.

FIG. 6 is a right side view of the gaming machine button panel of FIG. 1.

FIG. 7 is a front perspective view of a gaming machine button panel of another embodiment of our new design.

FIG. 8 is a front view of the gaming machine button panel of FIG. 7.

FIG. 9 is a top view of the gaming machine button panel of FIG. 7.

FIG. 10 is a bottom view of the gaming machine button panel of FIG. 7.

FIG. 11 is a left side view of the gaming machine button panel of FIG. 7.

FIG. 12 is a right side view of the gaming machine button panel of FIG. 7.

FIG. 13 is a front perspective view of a gaming machine button panel of another embodiment of our new design.

FIG. 14 is a front view of the gaming machine button panel of FIG. 13.

FIG. 15 is a top view of the gaming machine button panel of FIG. 13.

FIG. 16 is a bottom view of the gaming machine button panel of FIG. 13.

FIG. 17 is a left side view of the gaming machine button panel of FIG. 13.

FIG. 18 is a right side view of the gaming machine button panel of FIG. 13.

FIG. 19 is a front perspective view of a gaming machine button panel of another embodiment of our new design.

(Continued)

FIG. 20 is a front view of the gaming machine button panel of FIG. 19.

FIG. 21 is a top view of the gaming machine button panel of FIG. 19.

FIG. 22 is a bottom view of the gaming machine button panel of FIG. 19.

FIG. 23 is a left side view of the gaming machine button panel of FIG. 19; and,

FIG. 24 is a right side view of the gaming machine button panel of FIG. 19.

In the drawings, the broken lines depict portions of the article that form no part of the claimed design.
